DESIGN FOR A PERFUME BOTTLE CONTAINER

Edith Yorke von Sandor, New York, N. Y.

Application July 23, 1941, Serial No. 102,386

Term of patent 7 years

To all whom it may concern:

Be it known that I, Edith Yorke von Sandor, a citizen of the United States, residing in New York, in the county of New York and State of New York, have invented a new, original, and ornamental Design for a Perfume Bottle Container, of which the following is a specification, reference being made to the accompanying drawing, forming part thereof.

I claim:

The ornamental design for a perfume bottle container, substantially as shown.

EDITH YORKE von SANDOR.
